[57] CLAIM

The ornamental design for a combined ceiling fan and light fixture, as shown and described.

DESCRIPTION

FIG. 1 is a perspective view of a combined ceiling fan and light fixture showing my new design;

FIG. 2 is a bottom plan view of the combined ceiling fan and light fixture of FIG. 1;

FIG. 3 is a side elevation view of the combined ceiling fan and light fixture of FIG. 1, the other sides being identical to that shown; and,

FIG. 4 is a top plan view of the ceiling fan of FIG. 1.
